UNITED STATES PATENT OFFICE.

JOSHUA B. HALE, OF PROVIDENCE, RHODE ISLAND, ASSIGNOR, BY MESNE ASSIGNMENTS, TO TEXTILE ENGINEERING COMPANY, A CORPORATION OF RHODE ISLAND.

BRAIDING-MACHINE CARRIER.

Application filed April 28, 1920. Serial No. 377,195.

To all whom it may concern:

Be it known that I, JOSHUA B. HALE, a citizen of the United States, and resident of the city of Providence, in the county of 5 Providence and State of Rhode Island, have invented certain new and useful Improvements in Braiding-Machine Carriers, of which the following is a specification.

This invention relates to braiding machine carriers, and has for its object to provide in such a carrier a long yarn take-up arm pivoted on one side of the thread-mass and arranged to control the let-off mechanism, its free end extending to the opposite 15 side of the mass and adapted to engage the supply yarn and serve as a take-up for the same.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:—

Figure 1 is a side elevation partly in section illustrating the operation of my improved carrier.

Figure 2 is a plan view sectioned through the frame, on line 2—2 of Figure 1, showing the ratchet-toothed thread-mass supporting disk as engaged by the let-off pawl.

Figure 3 is a perspective view illustrating the hoop form of take-up arm.

Figure 4 is a section through the frame on line 4—4 of Figure 1, looking in the direction of the arrow.

Figure 5 is a perspective view of the let-off pawl.

With reference to the drawings, 10 designates the guiding base portion of the carrier, which engages the raceway of the machine, mounted on which guide is a central thread-mass supporting post 9 provided with a guide eye 8 at its upper end, and also mounted on this guiding base is a frame-portion 11 which in the present case, comprises a sheet metal strip, the forward end of which is turned to extend upward providing a yarn guide standard 12 which is provided with a guide-eye 13 at its upper end and a second guide eye 14 near its middle. The

portion of this standard below this middle 55 guide eye is slotted as at 15, which slot extends downward and into the laterally-extending portion 16 of this plate for the purpose presently described.

The rear end of this frame portion is also 60 turned to extend upwardly providing a bearing member 17, the sides 18 of which, see Figure 2, are turned forwardly providing bearing walls.

Between these side bearing walls I have 65 mounted a pawl member 19 on the pivot 20, its lower end 21 being provided with projections 22 adapted to engage the ratchet teeth 23 on the thread supply supporting disk 24 and are normally pressed into engagement with said ratchet teeth by the coil spring 25.

At the upper end of this rear bearing member I have pivotally mounted at 26 the rear end 27 of the take-up lever arm 28, 75 which arm is preferably formed from a strip of sheet stock bent into hoop form having a rearwardly-extending loop portion 27 which is provided with pivot eyes 29 through which the above-mentioned pivot 80 pin 26 passes.

These hoop-shaped arms 28 are adapted to encircle or extend around the opposite sides of the thread mass, which latter is indicated by dotted lines at 30 in Figure 1, and the 85 forward end of this hoop is provided with a forwardly-projecting neck portion 31 which is adapted to extend through the slot 15 in the standard 12, and the end of this neck is provided with a guide eye 32 through 90 which the thread 33 is passed for the purpose of taking up or providing a tension on the same.

Between the side arms of this forwardly-extending neck portion, I have positioned a 95 downwardly-extending plate 34 which, when the free end of the take-up is in its extreme low position, is arranged to extend through the lower portion of slot 15 into position to engage the stop motion on the machine (not shown) to arrest the action of the braiding machine.

In order to exert a tension on the yarn by causing a downward pressure on the free end of this lever, I have mounted a coil 105 spring 34 on the pivot pin 26 one end 35 of which is caused to engage the arm of the lever 28 while its opposite end 34 engages

one of the notches 37 in one of the side walls 18 of the aforesaid rear bearing member 17, the tension on which spring may be adjusted by shifting the end 36 into the different 5 notches 37.

A downwardly extending finger 39 is mounted on the pivoted end of this take-up arm, to engage the upper end of the pawl 17 and so withdraw its lower end from the 10 ratchet teeth 23 of the plate 24 to release the yarn-mass to rotate and supply more yarn, when the free end of the take-up arm is raised a predetermined distance.

My improved braider carrier has many 15 advantages over the carrier of the ordinary construction, among others being: first, it is provided with a take-up arm of extreme length that is, the arm is pivoted on one side of the thread-mass while its thread-engaging 20 end extends across to the opposite side of the mass and as the tripper finger is positioned on this lever adjacent its pivoting point the force applied to the take-up end of this lever, required to operate the let-off 25 through the tripper finger is reduced to the very minimum: Second, another advantage is that by this construction the operating spring acts at the pivoting point of this long arm, whereby the movement of this arm 30 causes the minimum amount of variation in the tension on this spring during a stroke of this arm from one extreme to the other: Third, another advantage of this construction is that the thread-mass may be kept very 35 low in the carrier: and fourth, the whole device may be made extremely light in weight whereby a very high velocity may be attained and the highest quality of work produced.

40 The foregoing description is directed solely towards the construction illustrated, but I desire it to be understood that I reserve the privilege of resorting to all the mechanical changes to which the device is 45 susceptible, the invention being defined and limited only by the terms of the appended claims.

1. A braiding carrier comprising a frame 50 for supporting a thread-mass, a let-off mechanism on one side of said mass, an arm extending around the mass having means at one end for operating said let-off, and means at its opposite end serving as a take-up for the yarn.

55 2. A braiding carrier comprising a frame for supporting a thread-mass, means to normally lock the thread-mass from turning, a spring controlled take-up arm in hoop form to extend around the thread-mass having means at one end for controlling said let-off lock, and means at its opposite end serving as a take-up for the yarn.

60 3. In a braiding carrier, a carrier-frame having a bottom plate for supporting a 65 thread-mass, means for normally locking

said plate from turning, a spring-actuated take-up arm pivoted at one end to the rear of said mass, between the ends of said mass, and arranged to operate said lock to let off the thread, the opposite end of said arm extending to the front of the mass and having means for engaging the thread to take up the same.

4. In a braiding carrier, a carrier-frame 75 having a toothed bottom-plate supporting the thread-mass, a spring-pressed lock pawl at the rear of and between the ends of the mass, engaging said teeth, a take-up arm having an opening at its front end through which the supply yarn is threaded, said arm being pivoted at its opposite end to engage and operate said pawl to let off more thread when the forward end is raised to a predetermined height.

5. In a braiding carrier, a carrier-frame 85 having a toothed bottom-plate supporting the thread-mass, a spring-pressed lock pawl at the rear of the mass engaging said teeth, a take-up arm having an opening at its front end through which the supply yarn 90 is threaded said arm extending in hoop form around the thread-mass and being pivoted at its opposite end to engage and operate said pawl to let off more thread when the forward end is raised to a predetermined 95 height.

6. A braiding carrier comprising a frame 100 for supporting the thread-mass, said frame comprising a standard having a take-up arm guide slot, a let-off mechanism on one side of the mass, a spring-pressed take-up arm extending around the mass having its yarn-engaging end operating in said slot and its opposite end pivoted to engage and operate said let-off.

7. A braiding carrier comprising a frame 105 for supporting the thread-mass, said frame comprising a standard having a take-up arm guide slot, a let-off mechanism on one side of the mass, a spring-pressed take-up arm 110 extending around the mass having its yarn-engaging end operating in said slot and its opposite end pivoted to engage and operate said let-off, and a stop-member at the free end of said arm.

8. In a braiding carrier, a frame comprising a base-plate, a front yarn guide standard and a rear upturned bearing member, a base-plate for supporting the thread-mass intermediate said standard and bearing member, 120 a pawl mounted in said member for arresting rotation of the mass, a spring-pressed let-off arm having one end pivoted in said member and arranged to engage said pawl, its opposite end extending forward of said standard and arranged to engage the yarn supply.

9. A braiding carrier comprising a frame 125 for supporting a thread mass, a let-off mechanism for said mass, and a movable 130

take-up member located between the ends of the thread mass for controlling said let-off mechanism.

10. A braiding carrier comprising a frame for supporting a thread mass and provided with a guiding base portion, said frame being adapted to occupy a position close to the top plate of the braiding machine, said carrier having a let-off mechanism, and a movable take-up member positioned between the ends of the yarn mass and adapted to control said let-off mechanism.

11. A braiding carrier comprising a frame for supporting a thread mass and provided with a guiding base portion, said frame being adapted to occupy a position close to the top plate of the braiding machine, said carrier having a let-off mechanism, and a member pivotally mounted between the ends of the yarn mass and adapted to govern the let-off mechanism.

12. A braiding carrier comprising a frame for supporting a thread mass and provided with a guiding base portion, said frame being adapted to occupy a position close to the top plate of the braiding machine, said carrier having a let-off mechanism, and an arm pivotally mounted near its end between the ends of the yarn mass and adapted to govern the let-off.

13. A braiding carrier comprising a frame for supporting a thread mass, a let-off mechanism at one side of said mass, an arm mounted between the ends of the thread mass and having means at one end to govern said let-off mechanism.

14. A braiding carrier comprising a frame for supporting a thread mass, a let-off mechanism at one side of said mass, an arm mounted between the ends of the thread mass and having means at one end to govern said let-off mechanism, said arm having means at its opposite end constituting a take-up for the yarn or thread.

15. A braiding carrier comprising a frame for supporting a thread mass, said frame having a transverse portion, and opposite upstanding portions, and a let-off controlling and take-up member mounted upon one of said upstanding portions and guided by the other upstanding portion the upstanding portion upon which said bearing is mounted extending above the base of the yarn supply.

16. A braiding carrier provided with a frame rigidly attached to the carrier body, said frame having an upstanding front portion provided with a slot and having an upstanding back portion providing a housing, a spring pressed pawl in said housing, an arm pivoted upon said back upstanding portion, and spring pressed to engage said pawl, said arm having its front end guided in said slot.

17. A braiding carrier provided with a frame rigidly attached to the carrier body,

said frame having an upstanding front portion provided with a slot and having an upstanding back portion providing a housing, a spring pressed pawl in said housing, an arm pivoted upon said back upstanding portion, and spring pressed to engage said pawl, said arm being of hoop form and encircling the thread mass and having its free take-up end movable in the said slot.

18. A braiding carrier comprising a frame for supporting a yarn supply mass, a movable take-up arm, said frame having front and rear upstanding portions, the latter extending above the lower end of the yarn supply mass and supporting said take-up arm above the bottom of said yarn supply mass, the front upstanding portion constituting a guide for said movable take-up arm.

19. In a braiding carrier having a take-up arm a frame for supporting a thread mass, said frame having front and rear upstanding portions, the former constituting a guide for the take-up arm and the latter constituting a support for said arm, said latter also constituting a housing for the let-off mechanism.

20. A braiding carrier comprising a frame for supporting a thread mass, said frame having front and rear upstanding portions, the former constituting a guide for a take-up arm and the latter constituting a support for said arm, let-off mechanism, and means whereby said arm controls said let-off mechanism.

21. A braiding carrier comprising a frame for supporting a yarn supply, a let-off mechanism for said mass, a hoop-shaped, spring pressed take-up member positioned to extend about the yarn supply between the ends of the latter having a projection controlling the let-off mechanism and adapted to release the same upon a predetermined extent of movement of the said take-up member.

22. A braiding carrier comprising a frame for supporting a yarn supply, a let-off mechanism for said mass, a hoop-shaped, spring pressed take-up member having a projection controlling the let-off mechanism and adapted to release the same upon a predetermined extent of movement of the said take-up member, said take-up member encircling the yarn supply between the ends of the latter.

23. A braiding carrier comprising a frame for supporting a thread mass, a let-off mechanism for said mass, a hoop-shaped, spring pressed, take-up member having a projection controlling the let-off mechanism and adapted to release the same upon a predetermined extent of movement of the said take-up member, said take-up member being mounted between the ends of the thread mass.

24. A braiding carrier comprising a

- frame for supporting a thread mass, and a movable arm constituting a take-up member for the thread, said arm being mounted between the upper and lower ends of the yarn supply and having a part adapted to engage the stop motion on the machine. 5 frame for supporting a yarn supply, said frame having front and rear upstanding portions, the rear upstanding portion extending above the base of the yarn supply, 40 and a take-up arm mounted upon said rear portion.
25. A braiding carrier comprising a frame for supporting a thread mass, and an arm constituting a take-up member for the 10 thread, said arm being mounted above the base of the yarn supply and having a downwardly extending projection which, when the take-up member is in its extreme low position, engages the stop motion of the machine. 15
26. A braiding carrier comprising a frame for supporting a thread mass, and an arm constituting a take-up member for the thread, said arm being mounted for movement and having a downwardly extending projection wholly positioned radially outside of the yarn mass and near the very end of said member and adapted to engage the stop motion on the machine. 20
27. A braiding carrier comprising a frame for supporting a thread mass, said frame having a transverse portion, an upstanding front portion provided with a guide slot for the take-up member, and an 30 upstanding rear portion providing a housing, a let-off mechanism, a pawl in said housing controlling said let-off mechanism, and a take-up member mounted upon said rear portion to govern said pawl and guided 35 at its take-up end by said front portion.
28. A braiding carrier comprising a
- frame for supporting a yarn supply, said frame having front and rear upstanding portions, the former extending above the base of the yarn supply, 45 and a take-up arm mounted upon said rear upstanding portion and hooped to extend about the yarn supply between the ends of the latter. 50
29. A braiding carrier having a frame for supporting a yarn supply, said frame having front and rear upstanding portions, the former extending above the base of the yarn supply, 55 and a take-up arm mounted upon said rear upstanding portion and hooped to extend about the yarn supply between the ends of the latter.
30. A tension member for the braiding carrier of a braiding machine mounted in a position such that it embraces the mass of yarn supply intermediate the extremities 55
31. A hoop shaped, spring pressed, tension member for the braiding carrier of a braiding machine mounted in a position such that it embraces the mass of yarn supply intermediate the extremities of said mass. 60
32. A braiding carrier including a support for a yarn supply mass, a rear upstanding member and a front upstanding member, and a spring pressed take-up member pivoted in said rear upstanding member and guided by said front upstanding member, 65 said take-up member functioning in a position intermediate the extremities of the yarn supply mass. 70

In testimony whereof I affix my signature.
JOSHUA B. HALE.
